UNITED STATES PATENT OFFICE.

WILLIAM DUCHEMIN, OF BOSTON, MASSACHUSETTS, ASSIGNOR TO WILLIAM S. BUTLER, OF SAME PLACE.

PLAITING-MACHINE.

SPECIFICATION forming part of Letters Patent No. 288,929, dated November 20, 1883.

Application filed July 20, 1883. (Model.)

To all whom it may concern:

Be it known that I, WILLIAM DUCHEMIN, a subject of Her Britannic Majesty, residing at Boston, in the county of Suffolk and State 5 of Massachusetts, have invented a new and useful Plaiting-Machine, of which the following is a specification.

The object of my invention is to provide an automatic plaiting-machine which will make 10 and sew simultaneously at any desired point between the marginal edges of the material employed either square or diagonal side or box plaits in any conceivable form or variety, with or without staying or cording. The 15 mechanism by which I attain these results is shown in the accompanying drawings, in which—

Figure 1 is a front elevation of the machine, showing the device as fitted for box-plaiting. 20 Fig. 2 is an inverted sectional plan of the table B B, showing the plaiting-carriage and driving mechanism for same. Fig. 3 is a sectional plan, showing feed-cam and connecting-arm. Fig. 4 is a vertical section on line 25 x x , Fig. 1, showing plaiting-carriage and its driving-pawls and ratchet, feed-jaws, and folding-fingers. Fig. 5 is a vertical section on line y y , Fig. 1, showing folding-cam, ratchet, pawls, and plaiting-cam. Fig. 6 is an inverted 30 plan of jaws, showing their mode of construction. Fig. 7 is a section of driving-shaft C, for reference. Fig. 8 is a vertical section of ratchet and folding-cam, showing the manner of securing the same. Figs. 9, 10, and 11. 35 are modified forms of folding-cams. Fig. 12 is a sectional plan of machine as fitted for knife or side plaiting. Fig. 13 is an inverted plan of the stationary guide, showing its construction. Fig. 14 is a vertical section of the 40 same. Fig. 15 is a view similar to Fig. 5, with working-pawl disengaged in readiness for knife-plaiting. Fig. 16 is a bottom plan of driving-pawls of plaiting-carriage out of gear. Fig. 17 is a side elevation of the same.

45 The same letters indicate similar parts throughout the several views, and in referring to them the words "outward," "inward," "front," "rear," &c., are used with reference to the position as referred to, Fig. 1, 50 whatever may be the apparent direction in special views.

The sewing mechanism shown in the drawings is similar to the Wilcox & Gibbs machine, but differs therefrom in some of the most essential details, as will be hereinafter 55 shown.

The plaiting mechanism is constructed as follows: A A, Fig. 1, represent the frame of the machine, to which is secured the table B B, and in which, in suitable bearings, the 60 driving-shaft C revolves. On the outer end of C is a fly-wheel, D, and eccentric E, which, by means of the connecting-rod F, give the required motion to the needle-arm G. The inner end of C terminates in an eccentric, a, 65 Fig. 7, the extreme end being provided with a central perforation, a^x, for the reception of the looper a', Figs. 1, 2, and 4. A feed-bar, b, is secured to the frame A, Fig. 2, by the screw-bolt b^x in such a manner that it can be 70 sent back (by the action of a spiral spring, b', placed in its interior) and forward (by means of an independent cam, n^y) in one-sixth of a revolution of the driving-shaft C. This feed-bar b has near its front end an oblong longitudinal slot, b^z, Fig. 4, which passes over the eccentric a, Fig. 7, and at its extreme front end, which terminates in a flat plate, is a similar slot, b^t, by means of which the plaiting mechanism receives its impetus. 75

Pivoted to a hanger, c, which is secured to the under surface of the table B B, is a flat plate, c', on the upper rear side of which is a pin, c^z, which enters the slot b^t, Fig. 7. At the lower front side of c', in perpendicular line with its pivot, is a similar pin, c^y, which passes through a perpendicular slot, c^x, Fig. 4, in a lever, c^t, pivoted to the lower end of the hanger c on the opposite side, and to the upper end of this lever c^t is fastened the driving-pawl c^z of a rack, 90 d^x, secured to the under surface of the carriage d. Against this rack the outer end of said pawl is held by a spiral spring, c^t. (See Figs. 1, 2, and 4.) The carriage d, Fig. 2, is secured to the under surface of the table B B by means of 95 the flat bearings d' d', Figs. 2 and 4, in such a manner that it can be sent inward the length of one tooth of the rack d^x at each revolution of the shaft C, and outward in one-quarter of such revolution by the lever c^t. The front end 100 of carriage d is provided with a set-screw, d^t, by means of which the different devices needed

for the varied qualities of the material used are secured to the carriage d , as hereinafter set forth. On the rear end, secured in position by a thumb-screw, d^5 , Figs. 3 and 12, is a stop-gage, d^6 , on the upper surface of which is a latch-clutch, d^7 , which curves over the side of the stop-gage and enters a notch, a^8 , on the edge of the carriage d , Fig. 4, for the purpose of retaining the gage in any position to which it is adjusted. On the lower surface of d^6 is a downwardly-projecting stud, d^9 , which descends through a slot in the carriage d , (shown in dotted lines,) and against which rests the inner end of the lever d^10 .

15 In close proximity to the rear bearing, d^1 , of the carriage d , pivoted to a lug proceeding therefrom, is a tripper, d^9 , Figs. 2, 3, and 4, which has at its extreme rear end an arm, e^1 , which passes between the carriage d and the 20 connecting-bar of the bearings $d^1 d^2$, and in the rear of the tripping-stud e upon carriage d , Fig. 2, the inner marginal edge of the front end of d^9 terminates in an inclined plane, e^2 , Fig. 2, which at the proper time presses down 25 a pawl, e^3 , Fig. 4, clear of the rack d^8 . This pawl e^3 is pivoted to the under surface of the front bearing, d^1 , Fig. 4, and is retained in position by the spring e^4 , and is provided at its inner end with a projecting finger, e^5 , inclined 30 upward at right angles. The lever d^10 , Fig. 2, is pivoted to the under surface of the table B B, its inner end bearing against a projecting stud, d^8 , as before stated, while on its outer end, secured by a similar joint, is the divided 35 lever-bar e^6 , the inner arm of which extends over and beyond the shaft C and rests in the latch e^7 , while its outer arm terminates about midway in a transverse face, a^9 , of such proportion that when the carriage d is brought in 40 the full length of its reach the face a^9 will pass freely into the throat of the plaiting-cam e^8 on the shaft C. The latch e^7 is pivoted to the side of the frame A, and is kept in position by a side spring, e^9 .

45 On the front side of the under surface of the table B B, at right angles with the carriage d , and secured by a working-bearing in the upper surface of the hanger e , is the shaft of a releasing-arm, e^10 , each end of which terminates 50 in an arm at right angles to the shaft. The outer and longer arm rests on the upper side of the latch e^7 , Fig. 2, while the short arm curves upward, as shown at b^1 , sufficiently to prevent the arm from coming in contact with the spur e^11 on the side of the carriage d until the carriage has made its home reach, when the arm, by the action of the spur e^11 , is sent down, and the long arm, pressing on the latch e^7 and depressing it, releases the divided lever-bar e^6 , which, by the action of the side spring, f , is then driven outward in position to be acted on by the working-surface of the cam e^8 .

The carriage d being in the position shown in Fig. 2, the operation is as follows: As the 65 shaft C revolves the eccentric a presses against the lower surface of the longitudinal slot b^2 in the feed-bar b and pushes it downward, thus

imparting, by means of the pin c^2 and slot b^4 , a forward motion to the arm c^3 , which acts on the lever c^5 and sends the working-pawl c^6 forward at an increased ratio compared with the feed, (see Fig. 4,) and brings the carriage d inward the length of one tooth of the rack d^8 , where it is held by the action of the pawl e^3 . This is continued until the tripping-pin e in the carriage d comes in contact with the arm e^1 and forces the inclined plane e^2 of the tripper d^9 under the finger e^4 of the pawl e^3 , thereby pressing it clear of the rack d^8 , and when the working-pawl c^6 makes its inward reach, 80 its end, coming in contact with the end of the pawl e^3 , is also pressed out of the rack, as shown in Figs. 16 and 17, and the carriage d is freed from the action of the pawls, and so remains for one-third of a revolution of the 85 shaft C. In this time the lever-bar e^6 , being released from the latch e^7 , is driven out, and the face a^9 , coming in contact with the working-surface of the cam e^8 , is, by its action, sent back, and the inner end of the lever d^10 forward, 90 and, pressing against the stud d^8 , sends the carriage d outward until the front end of the stop-gage d^6 , striking against the outer end of the sliding bar a^1 in the bearing d^1 , sends it inward against the arm e^1 and forces the tripper 95 from under the finger e^4 of the pawl e^3 , which is again brought into working position by the action of the spring e^4 , and the front end of the lever-bar e^6 is forced into the latch e^7 by the action of the inclined plane a^9 , Figs. 2 and 100 5, on the cam e^8 . The function of the stop-gage d^6 is to limit the rearward reach of the carriage d , which it does in this manner: There are as many notches a^9 on the side of the carriage d as there are teeth in the rack d^8 , the spaces 105 between the notches being equal to the spaces between the points of the teeth. Thus, when the latch d^7 is in the first notch in the rear end of the carriage d , it will make the longest reach, and when in the last notch the shortest reach, 110 and the plaits will each have as many stitches as there were teeth sent rearward in making them. In this manner the operator can produce as many differently-proportioned plaits as there are teeth in the rack d^8 , which may 115 be as many as fifty or more, if desired.

On the front side of the frame A A is a bracket, s^1 , having a horizontal shaft, f^1 , Fig. 5, on which the ratchet-wheel f^2 and folding-cam f^4 , Fig. 8, are made to revolve by the action of the pawl f^5 , the rear end of which is secured in a hanger, f^8 , Fig. 5, on the shaft s , Fig. 3, by passing through a slot, s^9 , in the lower side of said hanger, made in such proportion that it will permit the pawl f^5 to move 120 back and forth and up and down freely, but will prevent all lateral motion. Its front end terminates in a hook, f^9 . Its rear end is provided with a stud, s^1 . About midway it is bent in the form of a compound right angle, 125 which leaves a perpendicular face, s^2 , for the action of the projecting stud g in the cam e^8 , Fig. 5.

Pivoted to the under surface of an extension

of the hanger f^8 is a small clutch, g^x , which interlocks the stud g' in the pawl f^7 , in which position it is retained by the spring g^2 , Fig. 3, and is provided with an arm, g^3 , which reaches beyond the edge of the pawl f^7 . The top of the bracket s^5 , Fig. 3, terminates in a vertical face, to which is pivoted the lever g^4 , the under surface of which rests on the periphery of the folding-cam f^4 , while its outer end terminates in the arms $s^4 s^5$, Fig. 1, to the extreme end of which are secured, at right angles therewith, the folding-fingers $g^1 g^3$, Fig. 4. The lower arm, s^5 , plays on a pivot on the lever, and its action is limited by studs $g^5 g^6$, Fig. 1, in such proportion that when the arms $s^4 s^5$ are closed there will be space sufficient between the folding-fingers $g^1 g^3$ to let the material pass without contact, and when open to bring the lower folder in the required position to guide the fold forming the plait in the desired direction. The folding-fingers $g^1 g^3$ incline rearward gradually toward each other, and are flexible. The folding-lever g^4 is kept in contact with the cam f^4 by the pressure of the spring g^9 . The cam f^4 is held in position by means of the boss f^2 and steadyng pin f^5 of the ratchet-wheel f^2 , Fig. 8, and all back motion of the ratchet-wheel is prevented by the pawl f^6 , Fig. 1. Near the outer end of the shaft s is a circular block, k , Fig. 3, in which the spring s^6 is secured, its inner end pressing against the stud s^x in the rear end of the pawl f^7 .

In practice the operation of this combination is as follows: When the lever e^6 is released from the latch e^1 , Fig. 3, and is driven laterally outward, as described, its outer marginal edge comes in contact with the arm g^3 of the clutch g^x , and, forcing the clutch backward, releases the pin g' , and the pawl f^7 is sent forward by the action of the spring s^6 and latches into the next tooth of ratchet f^2 , in which position it is held by the spring s^7 until the projecting stud g , Fig. 5, of the cam e^5 , pressing against the perpendicular surface s^2 , sends f^7 back and brings the ratchet-wheel f^2 one tooth in advance.

This device is for box-plaiting, the plaits being reversed as follows: The ratchet-wheel f^2 having twelve teeth, the folding-cam f^4 is divided into twelve parts, and each alternate part projects, the intermediate depressions being formed by equally-inclining curved planes, as shown at f^4 , Fig. 15. Thus as each tooth of the ratchet-wheel is brought forward the arms of the lever g^4 are elevated or depressed, as subjected to the action of the cam f^4 or spring g^9 . When elevated, the extreme end of the folding-finger s^5 projects above the level of the needle-plate a^4 and the plait is formed over the feeding-jaws. When depressed, the end of the finger s^5 projects below the level of the needle-plate, and the plait is formed under the feeding-jaws, and so on alternately. This process forms regular box-plaiting. If a double box-plait is required, the projections and depressions on the cam f^4 must be equal

to the length of two teeth of the ratchet-wheel f^2 , Fig. 11. If a treble box-plait, the projections and depressions must be equal to the length of three teeth, Fig. 10, and so on to any practical amount. These changes, however, constitute but one class, for a folding-cam having a projection and depression equal to the length of one tooth and the next pair equal to the length of two teeth will give a single and a double box-plait alternately, thus changing the order of the plaits when made. In fact, there is no variety of this kind of plait that cannot be made by a change in the folding-cam; but it must be remembered that the teeth must be even numbers for even changes and odd for irregular changes. Thus a ratchet-wheel having eleven teeth will give two double and one single box-plait alternately, and so on in any variety. I have here given the smallest number of teeth. They may, however, be increased to any reasonable number, and of course the greater the number of teeth the greater variety of changes that can be made.

The feeding-jaws are constructed as follows: The plate h^x , Figs. 3, 4, and 6, of the lower jaw is composed of thin unyielding metal, and wide enough to feed in the widest material used, and of any desirable proportionate length. On its under surface is an immovable cross-bar, h^1 , Fig. 6, in the center of which, on the front side, is a transverse dovetailed slot, (shown by dotted lines,) in which the rear end of the goose-neck h^2 is fitted in such a manner that it can be pressed in or out smoothly for the purpose of adjusting the outer edge to suit the needle. Near its front end is a slot, h^3 , through which a screw that is threaded in a corresponding position in the goose-neck h^2 passes, and when the jaws are adjusted holds them in position. The plate h^4 forming the upper jaw is composed of thin elastic metal, and is provided with two transverse slots, $h^5 h^6$, of such proportion as will permit the material to pass smoothly through. About midway between the slots on the under surface is a cross-bar, h^8 , having a circular perforation at each end, through which pass the set-screws $w w$, which are threaded in corresponding positions in the cross-bar h^1 , fastened to the under jaw, h^x . Its under surface inclines upward from the front in such proportion that when the set-screws are tightened the lips of the jaws will be pressed closely together. (See Fig. 4.) These set-screws, by being set tight or loose, graduate the pressure for light or heavy material. The length of the plate h^4 must be such as will prevent the material from coming in contact with the carriage d . For the purpose of strength, the width must be such as will leave a marginal edge one-quarter of an inch beyond the ends of the slots. The slot h^3 in the rear edge of the jaws is designed to permit the passage up and down of a needle which carries the thread to sew the plaits into permanent shape as they are formed by the folding devices. In the drawings this slot is placed in the center of the rear edge of the jaws, and when in that position the seam

will obviously be in the center of the plait; but the plaiting may be done equally well, if desired, with a greater part of the jaws to the right or left of the needle, in which case the slot h^9 , though directly under the needle, is not in the center of the rear edge of the jaws, but a proportionate distance from it. This is most readily effected by having a set of interchangeable jaws any of which will fit on the carriage d , as described, but with the slot h^9 in different positions relatively to the width of the jaws; and in the same way for diagonal plaiting, jaws are provided whose rear edges incline more or less from the horizontal, as shown in dotted lines in Figs. 3 and 6. In adjusting the jaws the rear edges must pass the space of one stitch to the rear of the needle, the slot h^9 being set in such a position that the needle will pass in and out without touching either side. For knife or side plaiting with the jaws $h^x h^4$, the cam f^4 must be a plain smooth circle which will keep the under folding-finger, s^5 , in the proper position to insure the turn of the plait in the proper direction. For knife or side plaiting material too delicate to be drawn through the jaws $h^x h^4$, or that which is embroidered or has uneven edges, the working-pawl f^7 must be thrown out of gear and the jaws $h^x h^4$ and folding-lever g^4 removed, as shown in Fig. 15, and a device constructed as follows substituted. On the right-angular ends or projections of the cross-bar i , Fig. 12, which is fitted to the front end of the carriage d , secured thereto by set-screws, are the arms $i^x i'$, whose rear ends terminate in circular bearings. At the front end, on the outer side of the arm i^x , is a small angular spur, i^5 , and about midway on the side is a projecting stud, i^6 , the end surface of which is an inclined plane. The feeder i^t , Fig. 12, is made in such proportion that it will play freely between the raised edges of a stationary guide, i^7 , and is hung at its front marginal side on the pivots $i^2 i^8$, which play in the circular bearings spoken of as being in the rear ends of the arms $i^x i'$. Projecting from its inner side, near the pivot, is a flat plate, i^8 , which curves slightly downward at its outer end. The stationary guide i^7 , Fig. 12, is firmly secured to the table B B by screws passing through side lugs, $n n$, Fig. 12, and is made wide enough to permit the widest material used to pass freely between its marginal edges $n^x n^x$, which incline upward at right angles, Fig. 14. Its rear end passes the length of a stitch beyond the needle, and is provided with a rectangular aperture, c^8 , of such proportion that the side edges of the needle-plate a^4 will fit snugly against the sides and leave a space, c^9 , Fig. 12, in front of the needle-plate a^4 , and the front end of i^7 projects beyond the table B sufficiently to prevent the material from coming in contact with the carriage d . Just in front of the aperture c^8 is a transverse slot, through which a spring-folder, n^2 , projects sufficiently to insure the folding of the material in the required direction. On its under surface, lengthwise, is a rectangular groove, n^3 , Fig. 13,

in the center of which is a circular groove, n^4 . The groove n^3 is intended to guide a flat under stay to be sewed to the material being plaited when required, and the groove n^4 is to guide a cord for the same purpose. Close to and in line with the arm i^x is a straight flat bar, m , Fig. 12, swinging on the pivot m^6 , which secures it to the bed-plate B. At its free end, on the under side, is the downward-projecting stud m^x , and on the upper side is a raised block, m' , extending rearward about midway to the pivot, and on the inner side is an angular groove, m^2 , which terminates at its edge 80 in an upward-projecting lip. On the front end of m' is a slide, m^3 , having at its outer end an inclined plane, m^4 , of a reversed angle to that of the stud i^6 in the arm i^x , and is held in the required position by the set-screw m^5 . The swing of the bar m is limited by the stop m^7 . The function of this bar m is to lift the gripping-edge of the feeder i^t and prevent it from contact with the material during the outward reach of the carriage d . It operates as follows: 85 the mechanism being in the position shown in Fig. 12: At the finish of the home reach of the carriage d , the spur i^5 , pressing against the stud m^x , draws the bar m inward, and the inner side of the raised block m' passes under the projecting plate i^8 , and as the feeder i^t is again carried outward the curve on the end of i^8 enters the angular groove m^2 , and, being raised thereby, lifts the gripping-lip of the feeder i^t and holds it up during the outward reach of the carriage d until the inclined plane of the stud i^6 , coming in contact with the inclined plane m^4 on the slide m^3 , forces the bar m outward, whereupon the end of the projecting plate i^8 falls in the notch m^8 , releasing the feeder i^t , which is brought down on the material by the pressure of the spring-arms i^9 , which give the necessary pressure to feed in the material. 95

It will be readily seen that with this device two or three thicknesses of material may be interplaited, from the fact that the feeder, not being in contact with the material except when under pressure, cannot disarrange the material, and as the pressure is used exclusively for feeding the material in, and can therefore be much 100 heavier than the pressure on the jaws $h^x h^4$, (before described,) which on their outward reach measure the plait, sufficient pressure can be put on this feeder i^t to retain two or more thicknesses in position and deliver them accurately to the sewing mechanism. 115

By cutting an aperture in this device to correspond with the aperture o in the table B B, Figs. 2 and 3, and supplying the feeder i^t with a sliding under jaw, it will, with the aid of the mechanism already described for that purpose, box-plait as readily as the jaws $h^x h^4$. I prefer, however, to use the device, as shown, for the work named. For plaiting wide material, the side plates, o^x , Fig. 12, are placed at each 120 side of the needle-plate a^4 and a proportionate presser-foot used. For narrow material the side plates, o' , are removed, as shown in Fig. 3, and a narrow presser-foot used. 130

For side plaiting narrow material, proportionate guides p are used, and are secured in position in the guide i^7 by means of a steady-ing-pin, n^5 , passing into an orifice in said guide, 5 and an underlapping spring-leaf, n^6 , as shown in Fig. 14. For box-plaiting said narrow material with the jaws $h^x h^t$, the upper jaw, h^t , is removed and a proportionate jaw substituted.

- On the needle-plate a^4 , extending downward 10 in its front end, is a V-shaped groove, n^7 , Fig. 3, the vertex of which is in line with the needle. Through this groove n^7 the under cord-ing is led in position to be sewed to the material. A circular groove may be used for 15 this purpose; but the V shape is preferable to all others, because, as the sides are equal, large or small cord will be delivered under the needle with equal precision, and insure the stitch being in the center of the cord.
- 20 To operate with the entire device: If for box-plaiting, the carriage d is drawn out the full length of its outward reach, and the lever g^4 rests on a projection of the folding-cam f^4 , Fig. 1. The material is passed up through 25 the slot h^6 in the upper jaw, h^t , down through the slot h^5 , and out between the jaws $h^x h^t$ and under the presser-foot. The machine is then set in motion, and will take care of itself, all that the operator has to do being to see that 30 no accident happens, and that the supply of material is continuous. If for side plaiting, the pawl f^7 is thrown out of gear and the lever g^4 removed, as before described, and the carriage placed in the position shown in Fig. 35 12. The material is passed under the feeder i^4 and the presser-foot and the machine set in motion, as before. If an under stay is required, the stay is passed through the groove n^3 in the bottom of the guide i^7 , the aperture c^9 in front of the needle-plate a^4 , and thence 40 under the presser-foot. If an under cord also is required, it is passed through the groove n^1 in the guide i^7 , the V-shaped groove n^1 in the front end of the needle-plate a^4 , and under the 45 presser-foot. The sewing of the machine is timed so that the needle will enter the plait

just before the carriage starts on its outward reach, and will not come out again till that reach is finished. To accomplish this it is necessary to time the sewing apparatus twenty- 50 five per cent. quicker than the regular time used in the Willcox & Gibbs machine, before mentioned, and make the feeding device accord with it.

I claim—

1. An automatic plaiting-machine provided with the interchangeable feeding-jaws $h^x h^t$, the carriage d , for carrying said jaws back and forth under the action of its driving mechanism, and the folding fingers $s^4 s^5$, with their 60 operating mechanism, in combination with a reciprocating needle and its operating mechanism, for sewing the plaits when formed by said jaws and fingers, as herein described and shown. 65

2. An automatic plaiting-machine provided with a series of interchangeable cams and their operating mechanism, in combination with a pair of folding-fingers to act upon the material to be folded, and thus determine the character of the plaits produced, as hereinbefore described. 70

3. In an automatic plaiting-machine, the feeder i^4 , with its driving mechanism, the stationary guide i^7 , and folder n^2 , in combination 75 with the swinging bar m and operating devices, as herein described, and for the purposes specified.

4. The combination of the stop-gage d^6 , latch-clutch d^7 , stud d^8 , and carriage d , with their 80 operating mechanism, as herein shown and described.

5. In an automatic plaiting-machine, the stationary guide i^7 , provided with upright edges $n^x n^x$, the aperture c^8 , and with the rectangular groove n^1 and circular groove n^4 upon its under side, as and for the purposes specified. 85
